UNITED STATES PATENT OFFICE

EDGEHILL T. BURNSIDE, OF SHELBYVILLE, INDIANA

GRAVEL WASHING MACHINE

Application filed April 12, 1930. Serial No. 443,890.

This invention relates to machines for washing and sorting gravel, and removing finer or light material from coarse material.

An object of the invention is to provide a machine which is simple and accurate for separating trash and other fine particles from some coarse collection of material and is designed particularly with a view to its use in cleaning gravel for use in concrete work. Referring to the accompanying drawings which are made a part hereof and on which similar reference characters indicate similar parts,

Figure 1 indicates a longitudinal section 15 of the device,

Figure 2 a section on line 2—2 of Figure 1, and

Figure 3 a plan view of a portion of the device.

In the drawings numeral 10 indicates a tank which preferably has a sloping side 11. Into one side of the tank projects a supply chute 12 for the material to be washed and number 13 indicates an outlet chute for the dirt which is washed out of the gravel or other material which is cleaned. The top of the outlet chute is slightly below the level of the inlet chute as shown in Figure 2. Suitably mounted in bearings on the frame of the tank are rollers 14 and 15 which carry an endless conveyor 16. This conveyor consists of a number of sections having side portions 17 and end portions 18 which portions are secured together by means of hinged joints 19 to provide a chain-like scraper conveyor. The conveyor is driven by means of a belt 20 operating on a pulley 21. Any other suitable driving mechanism may be provided for operating the conveyor, that shown being one of several suitable conveyors. The roller 15 preferably is provided with a number of gears 22 which engage the hinge portions of the conveyor in order to drive it. The chute 12 delivers into a chute 23 which confines material so that it falls near the center of the box 10 so as to be picked up by the scraper conveyors and delivered up the outlet side 11 to a suitable receptacle not shown. Positioned beneath the stream and somewhat 50 to one side of the stream of incoming gravel

is a pipe 24 having a slot 25 positioned to direct a stream of water against the falling gravel, the force of the stream tending to drive trash and dirt which may aggregate with the gravel toward the outlet chute 13. 55 The pipe 24 is connected to a source of water under pressure sufficient to give the necessary force to the stream of water as it is projected against the falling gravel. From the foregoing description it will be clear that the 60 trash and other impurities which may be mixed with the gravel are forced in the direction of the outlet so that in case this material would not float, it nevertheless would be driven to the point at which it will be 65 caught in the stream of water flowing out of the tank.

While I have described this apparatus as applied to the washing of gravel for concrete and similar uses I do not limit it to the 70 specific art with which it has been described. It should be obvious that the machine could be used for many other purposes, such for example, as washing berries and fruits in which the trash would be washed up through the 75 body of water and the solid portions of fruit allowed to settle in the bottom of the tank and be conveyed out to a receptacle or to some other machine in which they are treated or to some other operation which may be 80 performed upon them. The machine may also be found of particular utility in preparing vegetables such as peas and similar vegetables for canning, from which it is necessary to separate trash and defective or small 85 peas from the solid ones.

It will be obvious to those skilled in the art that various changes may be made in my device without departing from the spirit of the invention and therefore I do not limit 90 myself to what is shown in the drawings and described in the specification but only as indicated in the appended claims.

Having thus fully described my said invention, what I claim as new and desire to 95 secure by Letters Patent is:

1. A gravel cleaning machine comprising a tank having a sloping bottom, a conveyor comprising a series of scoops movable through the tank to move the gravel along 100

said sloping bottom and out of the tank, a gravel inlet chute at one side of the tank, a pipe beneath said chute having an upwardly directed slot to direct water upwardly through the incoming gravel, a pair of guide partitions for directing the gravel into the path of water from said pipe in the tank and into the path of the conveyor, and an outlet chute positioned opposite the inlet chute for carrying off water and light material washed out of the gravel, substantially as set forth.

2. A gravel cleaning machine comprising a tank having a sloping bottom, a conveyor movable through the tank to move the washed gravel along said sloping bottom and out of the tank, a gravel inlet chute at one side of the tank, a pipe beneath said chute having a slot to direct water upwardly through the incoming gravel, a pair of guide partitions for directing the gravel toward a central place in the tank through the flow of water from said pipe and in the path of the conveyor, an outlet chute positioned opposite the inlet chute for carrying off water and material washed out of the gravel, and an inclined baffle plate secured in the tank adjacent the outlet chute and above said conveyor for directing water and trash washed out of the gravel upwardly toward said outlet chute, substantially as set forth.

In witness whereof, I have hereunto set my hand at Shelbyville, Indiana, this tenth day of April, A. D. nineteen hundred and thirty.

EDGEHILL T. BURNSIDE.
